APPARATUS FOR VAPORIZING HEAVY
LIQUID FUELS

Albert le Coënt, Henri Guillon, and René Roubinet, Paris, France, assignors to the Société Anonyme so-called: Office Central de Chauffage Rationnelle, Paris, France

Application April 6, 1951, Serial No. 219,738
In France April 3, 1950

2 Claims. (Cl. 158—53)

1
This invention relates to apparatus for the combustion of liquid fuels.

Normally, in the combustion of fuel oil, the oil is first subjected to atomisation, either by a fluid under pressure, e. g. air or steam, or mechanically, or by the two in combination. From the fuel oil burner there is then emitted a mist of very minute droplets of fuel, usually admixed with air, so that the combustion, once initiated, is capable of proceeding without further outside action of the mist thus discharged from the burner. The combustion process is extremely rapid, and it is indispensable that it should be completed before the droplets reach the end of their path within the combustion chamber.

In the case of tars and heavy fuel oils the pre-heating and atomization of the fuel do not overcome the necessity for very rapid combustion, as the droplets of oil are liable to burn if they are maintained in the midst of an oxidizing and very hot flame, this, therefore, involving a short flame and a very rapid combustion, so that the heating effect is unavoidably rough. When these requirements are not fulfilled, due either to premature cooling or to the supply of air being too small, soot will form and will be deposited on the parts of the mechanism. More particularly, it is not possible to obtain a long and waving flame of a neutral or reducing character combined with the generation of carbon monoxide and free hydrogen without the formation of considerable amounts of carbon black, the presence of which is objectionable, if not altogether harmful. The deposits result from a cracking of the heavier hydrocarbons which attends, and in most cases even precedes, the complete combustion.

It is the primary object of the present invention to provide apparatus for the combustion of liquid fuels, wherein these disadvantages are avoided.

The invention, therefore, resides in a method of effecting combustion of heavy liquid fuels, such as tars and fuel oil, characterized in that the liquid fuel is first converted completely into a gaseous mixture composed primarily of carbon monoxide and hydrocarbons by incomplete combustion thereof with the requisite amount of pre-heated air or other combustion-sustaining gas, whereupon combustion of the mixture is completed by any known method.

The liquid fuel may be preheated and injected, in the form of liquid filaments, together with pre-heated air into a furnace having refractory walls. In this case the air may be injected immediately adjacent the liquid filaments.

2
Air intakes may be so arranged that streams of air issuing therefrom sweep those portions of the furnace in which the carbon released by the conversion of the fuel has a tendency to settle.

In an alternative form of the invention the liquid fuel may be trickled in the form of a thin layer along surfaces in contact with gases or vapours, which are caused to flow in opposition to the direction of flow of the liquid fuel.

10 The invention also resides in a furnace for use in carrying out the method in question, the furnace having a refractory lining, at least one set of concentric tubes comprising a central tube for the introduction of liquid fuel and an outer tube forming together with said central tube an annular space for the introduction of air, and air inlet nozzles for directing streams of air towards that portion of the furnace on which the fuel introduced into the furnace impinges.

20 In a specific form of embodiment the furnace may be provided, in the interior, with a system of superimposed horizontal baffles, along which the liquid fuel is allowed to trickle in opposition to a combustion-sustaining current of gas ascending in a zigzag path between the said baffles.

Three examples illustrating the manner in which the invention can be carried into effect will be described in the following with reference to the accompanying drawings, in which

30 Fig. 1 is a vertical section of a furnace adapted for carrying out a first embodiment of the invention.

Figs. 2 and 3 illustrate a furnace employed in a second embodiment of the invention, Fig. 2 being a vertical section taken on the line 2—2 in Fig. 3, and Fig. 3 being a horizontal section taken on line 3—3 in Fig. 2.

Fig. 4 is a vertical section of a furnace suitable for carrying out a third embodiment of the invention.

40 According to the first example illustrated in Fig. 1, there is employed a producer comprising a furnace 1, which is composed of a refractory material. Preferably, the form of said furnace is that of a vertical cylinder. It is provided at its lower end with an orifice 2 for use in heating the furnace 1 to the desired temperature by means of an auxiliary burner or other known device. The fuel oil is preheated to a comparatively high

45 temperature, which, however, is less than that at which cracking commences. It is then supplied by a pipe 3 and fed into the furnace 1 through a tube 6 surrounded by an annular duct 7. Hot air or, for example, pure oxygen is fed to the intake 50 4 of the annular duct 7. A pair of nozzles 5 serve

to supply further amounts of air for a purpose to be described later. The gaseous mixture passes out through an outlet 8.

The fuel oil is injected into the furnace through the tube 6 in the form of a filament, which falls to the bottom 9 of the furnace. The oil enters a region of the furnace at which there is a very high temperature of 1100° C. or more. Accordingly, it undergoes an extremely sudden heating, which results in vaporization of the lower-boiling constituents attended by the deposition of solid carbon, and then in a cracking of a considerable portion of the hydrocarbons, which is also accompanied by the deposition of further amounts of solid carbon in a finely divided state. Preferably, the conversion of the fuel oil into a gaseous fuel should be completed during the passage of the filament of liquid fuel between the outlet of the feed tube 6 and the bottom 9 of the furnace. This requirement is fulfilled by the arrangement as described, as the fuel oil is introduced in the form of a fine jet or filament which presents a sufficiently large area to the action of the heat in proportion to the rate of flow. If desired of course, the oil may be introduced into the furnace through a plurality of feed tubes, so that the complete flow is divided into separate filaments of small section.

The high temperature prevailing in the fuel oil inlet chamber is obtained by combustion of the carbon to form carbon monoxide. It is necessary for the entire amount of carbon to be oxidized at this stage, with the exception of the small amount of carbon dioxide corresponding to the chemical balance, and that the oxygen should not combine with the hydrogen, at least in any appreciable amount. To satisfy these requirements air is injected in an amount corresponding to the desired reaction. Moreover, owing to the air being preheated to approximately 350°, and despite the wholly incomplete nature of the combustion, a temperature is reached which creates working conditions leading to a satisfactory balance between the carbon monoxide and the carbon dioxide formed. In the event that some of the oxygen reacts with hydrogen, the water vapour generated would in turn react with the carbon to form water gas.

In addition to the supply of air through the annular space surrounding the oil feed tube or tubes, air may be supplied by means of the nozzles 5, whereby the air is divided and discharged obliquely for the purpose of creating turbulence in that region of the furnace where carbon deposits would otherwise tend to form in consequence of the incomplete oxidation of the fuel oil, i. e., at the ends of the paths of the liquid filament or filaments through the furnace. The air supplied in this manner whirls around the fuel oil filament and deflects the oil vapours towards the high-temperature reaction zone.

The combustible gaseous mixture leaves the furnace through the outlet 8 and is fed to a burner of conventional kind.

In the second form of embodiment referred to there is employed a baffle furnace which is similar to the one illustrated in Figs. 2 and 3. The air is preheated by passing it through a jacket which is in contact with fins adapted to cool the baffle furnace, down with the liquid fuel trickles in the form of a film.

The fuel oil or similar higher-boiling liquid fuel is supplied through a pipe 11 provided with a control valve 12, and flows into troughs 13 75

provided with a weir, over which it trickles down the surfaces 14 which are provided with horizontal baffles 15. The surfaces 14 are slightly oblique, so that as the liquid nears the bottom and becomes more viscous it trickles over increasingly shorter baffles.

The air introduced through the pipe 16 sweeps over the vertical outer webs 17 and is heated thereby after which it enters the producer at the bottom thereof through a slit 18, from which point it rises to sweep over the baffles 15. The gases pass out by way of the outlet 19 and can then be fed to a burner of any known kind.

In the form of embodiment illustrated in Fig. 15 4 there is employed a hollow vertical cylinder 21 having a top pipe junction 22 through which the gases are discharged, and a lower socket 23 for connection with an auxiliary burner 24 of conventional design, by means of which the 20 gasification can be initiated rapidly and the temperature required therefor can be maintained contingently thereon by virtue of hot gases received from said burner. The liquid fuel to be gasified, for example fuel oil, is injected 25 through nozzle 27, or is allowed to fall in the form of a thin filament, coaxially with the body 21 of the furnace. The air necessary to gasify the oil or the coke which accumulates at 25 on the bottom of the cylinder 21 is injected through nozzles 26. The latter are directed towards the deposit of coke 25 in such a way that gasification of the coke is obtained.

For the purpose of achieving a richer gas the air injected into the furnace to gasify the coke 30 may be replaced partly or wholly by pure oxygen, whereby not only nitrogen in the air is eliminated, but at the same time the balance between carbon monoxide and carbon dioxide is displaced in a favourable direction owing to local elevation of the temperature.

If desired, of course, the furnaces employed in carrying the invention into effect may be modified in various ways to suit particular requirements, particularly as regards their geometrical 45 form, within the scope of the invention.

What we claim is:

1. Apparatus for producing a combustible gaseous mixture from heavy liquid fuels comprising a furnace, a fuel introduction pipe entering the top of said furnace, a plurality of horizontal baffles on opposing interior walls of said furnace, the baffles on one said wall being staggered with relation to the baffles on the other of said walls and forming a tortuous path through said furnace, a plurality of vertical exterior webs on said furnace, a closed vessel enclosing the bottom portion of said furnace and that portion having said external webs, said furnace having a slit in the bottom thereof intercommunicating said furnace and said closed vessel, a gas inlet at the top of said vessel, and a gas outlet at the top of said furnace.

2. Apparatus as claimed in claim 1, and wherein in said opposing interior walls are oblique with 65 respect to one another and the distance therebetween diminishes toward the slit in said furnace, said baffles being increasingly shorter toward the bottom of said furnace.
